UNITED STATES PATENT OFFICE

2,007,628

BUTTON

Warren C. Anderson, Belmont, Mass., assignor
to United-Carr Fastener Corporation, Cam-
bridge, Mass., a corporation of Massachusetts

Application November 5, 1934, Serial No. 751,501

6 Claims. (Cl. 24—90)

My invention relates to a novel ornament, button or the like made from a vegetable nut and the like.

In the drawing, which illustrates preferred forms of my invention:—

Figure 1 is a side view of a button formed from a whole castana;

Fig. 2 is a side view of a button made from a black walnut;

Fig. 3 is a button made from a whole pecan;

Fig. 4 is a section taken on the line 4—4 of Fig. 3;

Fig. 5 is a side view of a button made from a portion of the shell of a black walnut;

Fig. 6 is a back view of the button shown in Fig. 5;

Fig. 7 is a section taken on the line 7—7 of Fig. 5;

Fig. 8 is a side view of a button incorporating the cup of an acorn; and

Fig. 9 is a back view of the button shown in Fig. 8.

As shown by the drawing, the spirit of my invention may be embodied in several forms. The first of these forms is that of the complete nut as shown in Figs. 1, 2 and 3. The button shown in Fig. 1 is made by first grinding or otherwise smoothing the ridges, as at 4, cleaning the nut, and then polishing it with wax or other suitable polishing material. The final step is the fixing of the attaching member, which is preferably in the form of a screw-eye 2, and a cap 3.

The treatment of the black walnut, as illustrated in Figs. 2 and 4, is slightly different. The nut is first subjected to a sand blasting operation to remove any foreign matter that may have collected in the grooves 4 of the nut. The ridges 5 are then smoothed on an emery wheel, or by other means, until they present substantially smooth, flat, ridge-like surfaces. The button is then polished, or dyed and polished; and when completed presents a very striking appearance, since the ridges 5 remain light under polishing, while the grooves 4 take on a dark color.

The button in Fig. 3 is made from a pecan, and having a naturally smooth shell requires only a small amount of sanding or buffing to remove whatever roughness it may have. This type of button will take a high polish after it has been smoothed down properly. It is also provided with an attaching member for sewing it to a garment and the like.

Having described forms of my invention requiring the use of substantially a whole nut, I shall now proceed with an account of those

forms which comprise only the shell or a part thereof. The button shown in Figs. 5, 6 and 7 is formed from a black walnut, such as the one used in Fig. 2. The nut is first cleaned and smoothed down as described above, and then cut in half, preferably along the natural divide between the two halves of the nut shell. The nut will then present an appearance somewhat as shown in Fig. 6. The next step is to remove the meat from the shell and fill up the cavity thus formed with a plastic material 6, which subsequently hardens. That face of the nut is then sanded to a smooth flat surface and the whole polished as above. The attaching member is then inserted at the proper point, preferably in a part of the shell itself. 5

A still further form of my invention is made from the outer shell or cup of a common acorn. As shown in Fig. 8, the stem is removed from the cup as at 7 and the rim 8 is made even and smooth. The cup is then filled with plastic material, which adheres to the inside of the cup and forms a support for the attaching member as shown in Fig. 9. 15

I have found that buttons made as described above are very durable; will take practically any degree of polish; and are exceptionally attractive when applied to garments of leather and the rougher fabrics. Besides being used for buttons, these devices make excellent ornaments for collars of coats and the like when a pair of them are attached to the ends of a chain or cord. They are also useful as ear ornaments, watch-fobs, and in fact may be used wherever a decorative and durable ornament of this type is desired. 25

While I have illustrated and described preferred forms of my invention, I do not wish to be limited thereby, as the scope of my invention is best defined by the following claims. 30

I claim:—

1. A device of the class described comprising a shell of a vegetable nut, a filling for said shell composed at least in part of a self-hardening plastic material, and an attaching member secured to said shell. 40

2. A button of the class described comprising, in combination, a cup-like portion of the shell of a vegetable nut, a filling material filling the interior cavities of said cup-like portion, and an attaching member secured to that face of the button at which the filling material is inserted. 45

3. A button of the class described comprising a cup-like portion of the shell of a vegetable nut, a filling material filling the interior cavity of said cup-like shell portion, the outer surfaces of said shell portion being smoothed and polished, and an 50

attaching member secured to one face of said button for the purpose described.

4. A button device of the class described comprising a naturally grown nut member of the vegetable nut family, said nut having a cavity therein, a filling material within at least a part of said cavity, and an attaching member secured in said filling material and providing means by which the device is connected to a member to be buttoned.
5. A button of the class described comprising, in combination, a cup-like portion of the shell of a black walnut, a filling material filling the interior cavities of said cup-like portion and forming a relatively smooth surface coplanar with the rim

of said cup-like portion, an attaching member secured to said smooth face and presenting an eye protruding therefrom for the purpose described, and the ridges in the outer surface of the said cup-like portion being reduced to substantial smoothness and polished.

6. A device of the class described comprising, in combination, the cup-like portion of the outer shell of an acorn, the rim of said cup being so cut as to be substantially smooth, a filling material filling the cavity of said cup and presenting a surface flush with the said rim thereof, and an attaching member secured to that face of said device formed by said filling material.
